UNITED STATES PATENT OFFICE.

SAMUEL B. WILLIAMS, JR., OF BROOKLYN, NEW YORK, ASSIGNOR TO WESTERN ELECTRIC COMPANY, INCORPORATED, OF NEW YORK, N. Y., A CORPORATION OF NEW YORK.

AUTOMATIC TELEPHONE SYSTEM.

1,237,433.

Specification of Letters Patent. Patented Aug. 21, 1917.

Application filed January 14, 1916. Serial No. 72,135.

To all whom it may concern:

Be it known that I, SAMUEL B. WILLIAMS, Jr., a citizen of the United States, residing at Brooklyn, in the county of Kings and State of New York, have invented certain new and useful Improvements in Automatic Telephone Systems, of which the following is a full, clear, concise, and exact description.

10 This invention relates to telephone systems, in which the talking connection between subscribers' lines is established wholly or in part by means of electrically actuated switching devices.

15 The principal feature of the invention resides in the provision of means for controlling the operation of such electrically actuated switching devices over the third or non-talking conductor of the connecting circuits employed.

20 Other features, which result from or are incident to the main object above noted, will appear during the description of the invention.

25 Figures 1 and 2, with Fig. 1 at the left, diagrammatically indicate the apparatus and the circuits employed in carrying out this invention. At the left in Fig. 1, a line finder switch is diagrammatically indicated for connecting the calling line 1 with the trunk circuit 2. This means of connecting the line to the trunk, however, forms no part of the present invention, and could be accomplished as well by a line or trunk-finding switch, or even by a manual switch as a plug and jack, as the invention is equally applicable to telephone systems in which the mechanical switches are controlled by a central office operator as to full automatic systems.

30 Assuming now that the brushes 3, 4 and 5 of the finder switch are positioned on the contacts of the line 1, and that the side switch wipers 6, 7 and 8 have moved to position 4, a circuit will extend from battery, through the right winding of impulse relay 9, wipers 7, brush 4, over the left side of the subscriber's line, through the substation apparatus, back over the right side of the line, brush 5, wiper 8 and back to battery, through the left winding of relay 9. Relay 9 attracts its armature, and completes a circuit for the slow-release relay 10.

35 The calling subscriber now operates her

sending device, the circuits of which may be substantially as shown in patent to A. E. Lundell, No. 1,148,912. This causes a series of interruptions in the line circuit. With each interruption of the line circuit relay 9 retracts its armatures, but relay 10 being slow to act, holds up over these interruptions. It may be here noted that if this invention is employed in a semi-automatic telephone system, the impulse relay will not be connected to the talking conductors but will be controlled by the operator's sending device. With the first retraction of the armature of relay 9, a circuit is completed from battery through the rotary-stepping magnet 11 and the escape magnet relay 12 in parallel, and thence through wiper 13. A circuit is also completed from battery, through the release relay 14, to the wiper 13, the circuits being continued to ground through the front contact and armature of relay 10, and the back contact and armature of relay 9. Magnet 11 and relays 12 and 14 will be energized. Relay 14 will now be held up over a circuit extending through both front contacts and the armature of relay 10 to ground through resistance 15. This resistance 15, however, is so high as not to hold up the armature of magnet 11 or relay 12. Thus, when the relay 9 next attracts its armature, the armature of the rotary magnet 11 will fall off. Relay 12, being slow to release, will however hold up during the brief interruptions in its circuit at the back contact of relay 9. Thus, with each interruption in the line circuit at the operator's sending device, the brushes 16, 17 and 18 of the selector switch will be moved from one group of connecting circuit contacts to the next.

40 Any step-by-step, two-movement switch may be employed with the circuits shown. A switch of this general character is shown in patent to Keith and Erickson No. 815,176. However, in the description of the present invention the stepping magnet which first operates is described as the rotary magnet. That is, an around-and-up switch, instead of the up-and-around switch shown in the Keith *et al.* patent, is assumed to be employed in the present circuits. A switch of this character is shown in an application of Oscar F. Forberg, Serial No. 6,302, filed February 5, 1915. The side switch em-

ployed in the present invention may be of the type shown in the Keith *et al.* patent, or of the type similar to that disclosed in the Forsberg application.

- 5 Resuming now the description of the operation of the circuits, when the last impulse is sent, relay 9 will remain energized, holding open the circuit for the slow-release relay 12 and for the rotary magnet 11. The switch brushes will be stopped in operative relation, or in the present instance, just below the group of trunk contacts desired. When the relay 12 attracted its armature, it completed a circuit for the escape magnet 19, which now retracts its armature and moves the side switch wipers to position 2. In position 2 a circuit is completed from battery through the test relay 20, side switch wiper 21 and the normally-closed contact 22. Contact 22 opens on the first vertical step. The test relay in attracting its armature, completes a circuit for the escape magnet 19. A circuit is also completed from battery through the vertical stepping magnet 23, off-normal contact 24, wiper 25 and interrupter 26 to ground. The circuit of the vertical stepping magnet will be alternately opened and closed by the interrupter 26, causing the selector brushes 16, 17, 18 to move from trunk to trunk of the selected group. The lower or test contact of all busy trunks, will be connected to ground through resistance 15, by a circuit extending through the brush 18 and side switch wipers 21 and 13 of the selector switches associated with said busy trunks. Thus the test relay 20 will be held energized until the contacts of an idle trunk are engaged. The test contact of such a trunk will not be connected to ground and relay 20 will retract its armature opening the circuit for the escape magnet 19, which in turn retracts its armature and moves the side switch to position 3. The vertical off-normal contact 24 is closed during the upward movement of the switch, and opens on the tenth vertical step, in order to prevent jamming of the switch in case no idle trunk is found.
- 50 The calling line circuit has now been extended through to the connector switch shown in Fig. 2. If desired, however, other selector switches may be interposed between that shown at the right in Fig. 1 and the connector switch in Fig. 2.
- Assuming, however, that the present system discloses a thousand line exchange and that the series of impulses which operated the selector switch of Fig. 1 were the hundreds impulses, the subscriber would now operate his dial to send the tens impulses, causing a series of interruptions in the circuit of relay 9 as before. With the first retraction of the armature of relay 9, circuits will be completed from battery through

release relay 101, the rotary stepping magnet 102 and the escape relay 103. The circuit for the rotary magnet 102 passes through side switch wiper 104, where it joins the lead from relay 103. The circuit is then extended through the left armature and back contact of relay 105 to the lead from relay 101; the circuit being continued through brush 18, wipers 21 and 13, front contact of relay 10 and the back contact of relay 9. Magnet 102 and relays 101 and 103 are all energized. Relay 101 will be held up by the path to ground through resistance 15, in the same manner as relay 14. Relay 103 being slow to release its armature, remains up during the series of impulses. The armature of the rotary stepping magnet 102 is alternately attracted and retracted, causing the connector switch brushes 106, 107, 108 to be moved from group to group of the terminal contacts of the line terminating thereat. Upon the termination of the series of impulses, the rotary stepping magnet 102 will remain de-energized, thus stopping the switch brushes in operative relation to the tens group of contacts in which the wanted line terminates. When the armature of relay 103 was attracted, it completed a circuit from battery through the escape magnet 109, and the alternate contact and armature of relay 103 to ground, causing the energization of the escape magnet. Upon the termination of the series of impulses, relay 103 will retract its armature, opening the circuit for the escape magnet 109 and permitting the side switch to move to position 2.

The calling subscriber will now send the last or units series of impulses. With the first deenergization of the relay 9, the vertical magnet 110 and relay 103 will be energized in a manner similar to that described in connection with rotary magnet 102 and relay 103, upon sending the tens series of impulses. The brushes of the connector switch will now be stepped from line to line of the desired groups until they are positioned on the contacts of the wanted subscriber's line.

If the wanted line is already busy, the sleeve or test terminal thereof will be connected to ground through the brush 108 and wiper 111 in positions 3 and 4 of the connector switch connected thereto. If, however, the line is idle, its test terminal will be connected to battery only through its cut-off relay 112 and battery. When relay 103 was energized, due to sending the units series of impulses, the escape magnet 109 was energized in the same manner as before. Now, upon the retraction of the armature of relay 103, at the end of the unit series of impulses, a circuit is completed from battery through the winding of magnet 109, the normal contacts of relay 103, 130

test relay 105 and its right normal contact, wiper 111 and brush 108 to the test terminal of the called line.

As before stated, if the called line is busy, one of its multiple test terminals will be connected to ground, and test relay 105 will be energized; and in attracting its armature, will complete a locking circuit for itself and magnet 109, through its right alternate contacts and the side switch wiper 121. The magnet 109 being now energized, and the side switch being in position 2, the busy tone device 113 will be connected to the talking circuit through the left armature and front contact of escape magnet 109 and side switch wiper 114.

It will be noted that the busy tone device was connected to the upper conductor of the talking circuit, during the sending of the last series of impulses, but as the calling subscriber's receiver is short-circuited by contacts of the sending device during the transmission of the impulses, and as the side switch would be moved to position 3 simultaneously with the opening of the short-circuiting contacts at the sender, he would not hear the buzz if the wanted line was idle.

However, assuming that the line is busy and that the subscriber hears the buzz, and replaces his receiver on the hook, relay 9 will be deenergized and will interrupt and hold open the circuit for relay 10 which will retract its armature, thus opening the holding circuit for the release relay 14 of the selector switch, and the release relay 101 of the connector switch. Relay 14 in retracting its armature, completes a circuit from battery through the release magnet 27, rotary off-normal contact 28, closed on the first rotary step, and the armature and back contact of relay 14 to ground, thus causing the restoration of the selector switch. Relay 101, in retracting its armature, completes a circuit from battery, through release relay 115, rotary off-normal contact 116, closed on the first rotary step, the armature and back contact of relay 101, thus causing the restoration of the connector switch. It will be noted that the holding circuit, through the escape magnet 109 and the test relay 105, is maintained until the switch is released and the side switch brushes are returned to normal, thus preventing ringing on busy lines.

Assuming now that the wanted line is idle, its test contact will not be connected to ground. Thus relay 105 will not be energized and the escape magnet 109 will retract its armature, moving the side switch to position 3. In position 3 a circuit is closed from battery through the escape magnet 109, the armature and contact of trip relay 117 and side switch wiper 121 to ground. The escape magnet 109 attracts its armatures and completes a circuit from the generator 118, through trip relay 117, the right armature

and contact of the escape magnet 109, side switch wiper 119, brush 107, over the right side of the subscriber's line, through the bell of the wanted subscriber's substation set, back over the left side of the line, brush 106 and side switch wipers 120 and 121 to ground. This will cause the operation of the bell of the wanted subscriber. The busy tone device will not be connected to the talking conductor at this time, as the side switch is in position 3.

Upon the closing of the called subscriber's hook switch, the increased flow of current through the trip relay 117 will cause it to attract its armature, thus interrupting the circuit for the escape magnet 109 and causing the side switch to move to position 4, in which position the talking circuit will be established from the calling to the called line. Talking current is supplied to the calling subscriber through the windings of the impulse relay 9 and to the called subscriber through resistances 29 and 30. Busy potential will be supplied to the test contact of the called line through side switch wiper 111 in positions 3 and 4.

By the present invention, a telephone system is provided in which the switches, used in establishing a connection are controlled solely over the third or non-talking conductors of the connecting circuit. That is, the impulses for setting up the connection are transmitted over the third or test conductor, and the release of the switches is controlled over this same conductor, thus avoiding the necessity of associating any operating magnets or relays with the portion of the talking circuit extending to the called subscriber which is physically disconnected from the portion connected to the calling subscriber.

What is claimed is:

1. In an automatic exchange system, subscribers' lines, means including a selector switch for establishing a connection from one of said lines to another, a connecting circuit extending to said selector switch, said connecting circuit including a non-talking conductor, a stepping magnet for said selector switch connected directly to said non-talking conductor, and means for transmitting impulses over said conductor to operate said stepping magnet.

2. In an automatic exchange system, subscribers' lines, means including a selector switch for establishing a connection from one of said lines to another, a connecting circuit extending to said selector switch, said connecting circuit including a non-talking conductor, a stepping magnet for said selector switch connected directly to said non-talking conductor, means for transmitting impulses over said conductor to operate said stepping magnet, a release magnet for said selector switch, and means for con-

trolling said release magnet over said non-talking conductor.

3. In an automatic exchange system, subscribers' lines, means including a selector switch for establishing a connection from one of said lines to another, a connecting circuit extending to said selector switch, said connecting circuit including a non-talking conductor, a stepping magnet for said selector switch, a release magnet, a release relay for controlling said release magnet, said stepping magnet and said release relay being connected in parallel to said non-talking conductor, means for transmitting impulses over said conductor to operate said stepping magnet, and means for controlling said release relay over said conductor.
4. In a telephone exchange system, a plurality of lines, means including electrically-operated switches and connecting circuits for establishing connection between said lines, said connecting circuits each comprising a pair of talking conductors and a non-talking conductor, an impulse relay, a stepping magnet associated with each connecting

circuit connected directly to said non-talking conductor, and means for operating said impulse relay to operate said stepping magnets successively to cause the operation of said switches in establishing a connection. 30

5. In a telephone exchange system, a calling subscriber's line and a called subscriber's line, means including a series of electrically-operated switches and connecting circuits for establishing a connection from said calling line to said called line, said connecting circuits including a non-talking conductor, a stepping magnet and a release magnet for each of said switches, a relay for controlling each of said release magnets, 40 said stepping magnets and relays being connected in parallel to said non-talking conductor, means for transmitting impulses over said conductor to operate said stepping magnets, and means for controlling said release relays over said conductor. 45

In witness whereof, I hereunto subscribe my name this 13th day of January, A. D. 1916.

SAMUEL B. WILLIAMS, JR.
